UNITED STATES PATENT OFFICE.

CHARLES GÉGAUFF, OF MULHOUSE, FRANCE, ASSIGNOR TO SOCIÉTÉ ALSACIENNE DE CONSTRUCTIONS MÉCANIQUES, OF MULHOUSE, FRANCE.

MEANS FOR CONTROLLING THE NIPPERS IN HEILMANN AND LIKE COMBERS.

Application filed August 16, 1926, Serial No. 129,479, and in France August 19, 1925.

The present invention relates to combers of the Heilmann type in which the attaching and detaching mechanism consists of a pair of rollers which in practice are grooved 5 and an interposed leather belt, and in which the nippers holding the yarn to be combed are given an alternating translatory movement from the combing position to the detaching position, and vice-versa, the movement 10 during combing being tangential to the circular comb.

In this type of comber the detaching means and the circular comb are generally fixed in space, i. e. the axis of the bottom detaching roller and the axis of the circular comb retain the same position in space while the nippers are moved, as also the cap comb.

The opening and closing of the nippers are effected during displacement of the latter and in order the better to present the lap to the detaching rollers it is necessary that in proximity to these rollers, the path of movement of the end of the lower jaw of the nipper should be of substantially the same direction as the lap, while, on the other hand, in the combing position this path should be directed tangentially to the circular comb so as not to risk damaging the needles of the circular comb in case of accidental movement of the nippers out of their proper path, this being always a possibility having regard to the heavy weight of the nippers in movement.

Finally, it is still necessary that this latter part of the movement towards the circular comb should be effected by the end of the upper jaw, which should then brush the points of the needles of the circular comb while the lower jaw should then press against the upper jaw to grip the lap being combed. The upper jaw of the nippers should take a particular path, of S-shape, i. e., two curves, concave and then convex downwardly 40 terminating tangentially of or concentrically 45 with the circular comb and only the upper jaw should effect and possess this latter tangential movement.

The present invention has for its object to obtain in a more perfect manner than in known arrangements the trajectory described 50 by the upper nipper when passing from combing to detaching position and vice-versa.

The accompanying drawing illustrates by 55 way of example one embodiment of the in-

vention. This figure is a diagrammatical sectional view taken on a plane perpendicular to the circular comb. The feeding means of textile matters to the comb are not shown in the drawing, said feeding means being 60 in no direct relation to the object of the invention.

Referring to the drawing, a_1 is a circular comb mounted on the shaft a ; b and b_1 are the detaching rollers; c_1 is a belt connecting 65 the roller b and a somewhat larger tensioning roller c and conveying the combed matters.

The mechanism comprises a lower arm u , a cam-like profiled path u_1 being provided 70 at the lower side of said arm and resting on a roller x_1 , said arm carrying the lower jaw e_1 of the nippers. This arm is pivoted at i to a lever k_1 keyed on and receiving from the shaft k a reciprocating angular movement of the extent $i-i_1$.

A second arm y carrying the upper jaw e of the nippers, is pivoted at h to the first mentioned arm. This second arm is provided with a profiled (cam) path m , m_1 80 applied against the roller l_1 the pin l of which is fixed to the frame of the comber. A return spring n attached to the frame of the comber at a convenient point n_1 applies the upper arm against the roller l_1 .

When in combing position (as shown in the drawing) the two nippers are pressed against each other with the yarn to be combed interposed between them and in a proximity of the needles of the circular comb. When in detaching position, the nippers are brought in front of the detaching rollers whereby the last catch hold of the combed yarn. During the movement of the nippers from the combing to the detaching position and vice-versa, the lower end of the upper jaw e describes the trajectory f_1, f_2 which has the shape of a lying S, that is to say is formed of two curves, concave and then convex downwardly. When arriving in the vicinity of the combing position, the lower end of the upper jaw e moves tangentially to the circular comb.

The roller x_1 forms a rest for the cam path u_1 of the lower arm u of the nippers, the pin of this roller being carried by a spring blade y held back by another blade z . The spring blade y serves as a flexible member when the nippers are shut and when the yarn to be combed is of abnormal thickness.

In that case the roller will yield to a certain extent while continuing to exert, during the combing, the spring pressure ensuring a good gripping of the yarn.

5 In a modified construction, the roller α_1 may be mounted on a journal provided on the arm carrying the lower jaw of the nippers, with or without an interposed spring, the cam-like rolling path u , u_1 being then 10 fixed to the frame of the comber for instance (with or without an interposed spring).

What I claim is:

In a comber of the class described, in combination with a revoluble combing cylinder and a pair of detaching rollers, a nipping mechanism comprising a lower arm and an upper arm pivotally connected to said lower arm and means to impart reciprocating motion to the lower arm, said arms being provided respectively at their free ends with 20 lower and upper jaws, a roller on which

the lower arm travels, said arm having a cam face bearing on said roller and arranged to cause the free end of said jaw as 25 the same passes over the combing cylinder to move in a compound curved path tangential to the upper side of said combed cylinder and leading to a point opposite the lower detaching cylinder, and a roller which bears on the upper side of said upper arm, 30 said upper arm having a spring arranged to raise the free end of said upper arm as it approaches the detaching rollers and thereby causing the upper jaw to be raised from 35 the lower jaw, said upper arm having a cam surface bearing under said last named roller and constructed and arranged to permit such upward movement of the free end of 40 the upper arm with its upper jaw as the said arms approach the detaching rollers.

In testimony whereof I affix my signature.

CHARLES GÉGAUFF
